UNITED STATES PATENT OFFICE.

MYLES F. MORAN, OF LYNN, MASSACHUSETTS.

DIE AND DIE-STOCK.

1,243,543.

Specification of Letters Patent. Patented Oct. 16, 1917.

Application filed June 30, 1915. Serial No. 37,354.

To all whom it may concern:

Be it known that I, MYLES F. MORAN, a citizen of the United States, and resident of Lynn, county of Essex, State of Massachusetts, have invented an Improvement in Dies and Die-Stocks, of which the following description, in connection with the accompanying drawing, is a specification, like characters on the drawing representing like parts.

This invention relates to improvements in combined tools and particularly those of the type which are employed by plumbers and other artificers in metal.

In performing repair work on plumbing and the like the workman is required either to carry a large number of tools such as dies, taps, wrenches, cutters, drills, etc., or else is likely to find it necessary to return to the shop for the proper tools for his work, for the reason that when he is sent out upon a job he is unfamiliar with the type of plumbing which he is to repair, and since different buildings have plumbing materials of different kinds no one set of stock tools has been devised which are adapted to perform the work required upon the various types and sizes of fittings.

The principal object of the present invention is to provide a compound tool comprising a head and an actuator therefor which may be used in connection with various accessories easily contained in the usual plumber's kit which will enable the workman to readily repair almost any defect which he may find without the necessity of returning to the shop for the proper tools or taking the parts of the installation to the shop for threading, boring, cutting or other repair.

By the provision of such a compound tool it will be readily understood that much time otherwise lost will be saved and inconvenience resultant upon the shutting off of water or gas for a relatively long period of time will be overcome.

With these ends in view the present invention comprises a rotatable head which may if desired be made in sections and which is adapted to be actuated either by a handle or handles connected directly thereto or by a pipe wrench of the usual character but preferably of the "Parmelee" type. This head is designed to provide a screw thread cutter or to be utilized as a support for a chuck,

boring tool, such as an auger or drill, or as a member of a jack or in various other relations within the usual requirements of the plumber or other workman in metal.

While it is impossible to disclose in this application all of the uses to which the compound tool forming the subject matter of this invention is adapted to be applied, or all of the various forms which the compound tool may take I have illustrated herein in a few of the preferred embodiments and uses of the invention. It will however be understood that the claims of this application are to be construed to cover other forms as well as various and sundry uses to which the same may be applied within the scope of their terms and that the object of this invention is broadly to provide a combined tool capable of various uses and operable by suitable actuators of various types including the chain or strap wrench, the "Parmelee" wrench and various other types of wrenches.

In the preferred embodiments of the invention however the cutter is provided with two handles preferably in axial alinement, one or both of which are detachably secured to an intermediate flexible member whereby one of said handles may be easily removed in case of necessity but both may be generally used to provide for an accurate operation of the various tools which are operable through the head which forms the salient portion of said compound tool.

In the drawings;

Figure 1 is a side elevation of a compound tool comprising two handles connected by flexible head embracing members, the head being shown in the form of a cylindrical thread cutting die,

Fig. 2 is a view of a modified form in which a handle is connected directly to a projection upon a thread cutting die which is disclosed as engaging the end of a pipe,

Fig. 3 is a longitudinal vertical section of one of the preferred forms of head including thread cutting members and guiding bushings for retaining the article, e. g. a pipe or rod, in proper position in relation to the thread cutters.

Fig. 4 is a modified form of thread cutting die in which thread cutters are formed rigid with the members of the flexibly connected series of links two of which are provided with actuating handles.

Fig. 5 is an end view of a cylindrical head formed in three sections which are hinged together, the free ends being secured in proper position by dowel pins and sockets.

Fig. 6 is a detail sectional view of a pivotally mounted thread cutter with means for varying the inclination thereof, said thread cutter being adapted to be applied to the cutter carrying links of Figs. 4 and 5.

Fig. 7 is a detail view of the cutter illustrated in Fig. 4 with the links in extended position.

Fig. 8 is a longitudinal sectional view of the head shown in Figs. 3 or 5 provided at one end with a chuck to receive various tools and at the other end with a tail stock and feeder to adapt the same for boring, reaming and various other uses, showing also in dotted lines a smooth hand grip.

Fig. 9 is a longitudinal sectional view of the form of head illustrated in Figs. 3 and 5 provided with a sleeve having an internal bushing, the sleeve being connected to the head by screw threaded union and the bushing being provided with centering screws adapting the same to be attached to the pipe to be threaded in such manner that the head will be advanced upon the pipe as the screw threads are cut thereon, and,

Fig. 10 is a detail view of a usual threading die engaging and supporting a head such as that illustrated in Figs. 3 and 5 and thereby providing means for cutting a screw thread upon a pipe of smaller diameter than the diameter of said usual die.

Fig. 11 is a view of the head shown in Fig. 5 with adjustable threading dies assembled in the actuator shown in Fig. 1,

Fig. 12 is a detail view of the head shown in Fig. 11 in open or extended position,

Fig. 13 is a vertical longitudinal section of said head embracing the shank of a chuck, the latter being shown in elevation,

The compound tool illustrated herein comprises a tool carrying head and a handle member or actuator adapted detachably to engage the same comprising, preferably a pair of handle members connected by a series of intermediate links in such a manner that the handles will be in axial alignment as illustrated in Figs. 1 and 4.

As illustrated in Fig. 1 of the drawing the actuator comprises a handle or stem 1 having preferably a slotted enlarged end 2 provided with a shouldered projection 3, the slots in said end portion being adapted to receive extensions 4 of a link 5 forming one of a series of gripping members, a sleeve 6 preferably having a knurled portion 7 being screw threaded upon said stem 1 and adapted to actuate a slide 8 which serves in coöperation with the shoulder 3 to lock the gripping members the same as in the "Paramelee" wrench.

The link 5 is hinged at its opposite end

to a link 9 which in turn is hinged to a link 10, the free end of the link 10 being provided with a projection or shoulder 11 adapted to be engaged by the shoulder 3 upon the end of a handle member 2. The link 9 preferably is provided with a boss 12 to which a handle 13 is connected by a screw threaded union. The handle 1 may be detachably secured to the link 5 by a pin 14 which preferably is provided with a split ring 15 (see Fig. 7) seated partly in a groove in the pin and partly in a groove in the hinge extension of the link 5.

As illustrated in Figs. 1 and 11 the links 5, 9, and 10 are shown as embracing and operatively engaging a head which is provided with inwardly extending thread cutting members engaging the end of a pipe P.

The head, which forms one of the principal features of this invention is shown in detail in different forms in Figs. 3, 5, 12 and 13. As shown in Fig. 3 the head 16 consists of a hollow cylindrical member having inwardly projecting ribs 20 provided adjacent one end with screw cutting teeth 21, the remaining portion preferably being smoothly concaved and forming means adapted to guide the pipe P or rod to be screw threaded. The depression or interval 22 between the ribs 20 serves the double purpose of forming a clearance for the chips which are cut by the thread cutting members and also providing a seat for a chuck for holding other tools which will hereinafter be described.

The exterior of the head may be of any convenient form but preferably is cylindrical and is provided with screw threaded portions 23, 24, at its ends and an intermediate preferably smooth cylindrical portion 25 adapted to be gripped by the flexible members of the actuator above described.

As illustrated in Figs. 5, 12 and 13 the head may be constructed of a series, preferably three, longitudinal sections 26, 27, 28 the adjacent edges of the sections being provided with interlocking projections 29, 30, which may be secured together by pins 31, the free ends of the links 26 and 28 being secured in proper relation by a dowel pin 32 carried by one of the members entering a slot 33 in the other member.

The overlying member 26 desirably may be provided with an undercut portion or thumb recess 34 by means of which the sections may be opened, as illustrated, for example, in Figs. 7 and 12.

The head illustrated in Figs. 5, 12 and 13, like that illustrated in Fig. 3, may be and desirably is provided with external screw threads at the ends for purposes hereinafter to be described. In using a head of the type illustrated in Fig. 3 the pipe or rod to be screw threaded will be inserted through the lower portion of the cylindrical member until 130

the end thereof engages the innermost cutters of the dies 21, the pipe being clamped against rotative movement. The actuator, which preferably is of the form illustrated in Fig. 1 but which may be a pipe wrench of the usual character such as a Stillson wrench, or a chain wrench, is then caused to grasp the smooth cylindrical portion 25 of the head and the head rotated relatively to 5 the pipe, so that the cutting dies thereupon engage and screw thread the end of the pipe in the usual manner.

During the screw threading operation the curved surfaces of the ribs 20 loosely engage 10 the exterior of the pipe and maintain the cutters in proper position relatively thereto.

It will be obvious that the same operation 15 may be performed by the use of the head disclosed in Figs. 5 and 12 and that the latter has an additional inherent advantage in 20 that when the thread has been cut the actuator may be removed and the head then opened and removed from the pipe without the necessity of backing the same off as is the 25 case when an integral cylindrical head such as that shown in Fig. 3 is used.

In order to insure the proper feeding of 30 the cutter upon the pipe I may provide a threaded collar 35 such as illustrated in Fig. 9 which is provided at one end with screw 35 threads 36 adapted to engage the screw threads 24 upon the end of the head opposite to that which contains the screw threading dies 21. The collar 35 is preferably internally screw threaded at its opposite end and provided with a bushing 37 having an aperture 38 of the diameter of the pipe to be threaded.

Set screws 39 preferably three in number 40 passing through the collar and bushing may serve to center and hold the sleeve 35 rigid in respect to the pipe. When the sleeve has thus been affixed to the pipe the head 16 is placed over the end of the pipe until the 45 screw threads 24 thereon engage the threads 36 of the sleeve. It is then screwed up by hand until the cutters 21 reach the end of the pipe, whereupon the actuator is clamped upon the central portion 25 of the head and 50 the head rotated. This rotative action causes the thread cutters to engage and cut the threads upon the end of the pipe. In the meantime the engagement of the threads 24 of the head and 36 of the sleeve act as a 55 feeding means and since these threads are of the same pitch as the threads of the die members 21 the cutter will be fed accurately along the pipe as the screw threads are being cut, thus forming quite as accurate a thread 60 upon the end of the pipe as if the same were cut in a regular screw threading machine.

The external screw threads 23 at the end 65 of the head also provide means whereby the tool may be used to cut threads upon the end of a pipe located in an otherwise inacces-

sible place, as for example, in a hole in the floor beneath the surface thereof or in a partition or wall in which case an internally threaded tube may be screwed upon the end of the head so that the head may be inserted 70 in the aperture or hole to engage the end of the pipe to be threaded and the head rotated by a suitable actuator applied to the projecting tube.

Frequently in plumbing repair work it is 75 found necessary to bore a hole in some portion of the iron work or in the wood work which lies adjacent to the piping which is being repaired or installed, which requires the use of a boring tool. The necessity for 80 such apertures is rather infrequent and the workman will be without a boring instrument. In order to provide for such exigencies I have provided the head 16 above described with attachments which enable it to 85 be used both as a boring instrument for wood or iron.

It will be remembered that the ribs 20 project inwardly from the inner concaved surface of the head leaving recesses there-between which in the use of the cutting die form clearance spaces for the die. These recesses may also be used to receive ribs 40 upon the body 41 of a chuck, the grooves 42 intermediate of said ribs embracing the 95 ribs 20. The body portion 41 of the chuck may be made to fit tightly the interior of the head or if desired may be made slightly tapered to insure a tight fit, suitable jaws being carried in the body of the chuck to 100 engage the stem 43 of any usual tool, the jaws being clamped thereupon in the usual manner by a knurled collar 44 of the usual type. The opposite end of the head in such case desirably is covered by a cap 45 which 105 is provided with internal threads to engage the threads 23 of the head 16. The cap 45 may present a smooth surface 45* if a wood boring tool is to be used and may be provided with a central screw threaded aperture 46 adapted to receive a tail stock 47 having a conical end 48 which may be caused to engage a member of a clamp or any other suitable abutment.

When the tool is used for boring wood 115 the proper tool is clamped in the head and forced against the wood by the pressure of the hand of the operator against the cap 45 the actuator being applied to the cylindrical portion 25 of the head and the latter rotated 120 either by a complete rotary or by a reciprocating movement of the actuator. If the head is to be used with a metal boring tool the tail stock will be retracted until it engages an abutment or the arm of a suitable 125 clamp and the tool rotated in the same manner. In such case the rotation of the head may serve in a measure to feed the tool forward but probably the end 48 of the tool will rotate freely upon the abutment 130

with which it has a small bearing surface engagement. In such case the tail stock 47 may be rotated by thrusting a nail or an awl into apertures 49 in the angular head 50 of the tail stock; or the tail stock may be rotated by a usual small wrench in an obvious manner.

The head 16 may also be used in connection with the usual form of screw cutting die, such as illustrated in Fig. 10, for cutting threads upon pipes smaller than those which may be cut by the usual die.

In Fig. 10 an ordinary type of die for cutting threads is illustrated which is in the form of a square steel block 51 having four inwardly extending thread cutting members 52. Assuming for example that this die is adapted to cut the threads upon a one-inch pipe and the workman finds it necessary to cut the thread upon a three-quarter inch brass or copper pipe. The head 16 may be screwed into the die 52 and actuated by the usual die stock which embraces the square die cutter. In such case the resistance between the threads on the head 16 and the thread cutting dies 52 will be much greater than the resistance of the metal of the softer pipe against the cutters 21 of the head 16 so that the pipe may be screw threaded without injury to the main die 51.

In some instances it is desirable to have means for cutting a tapered thread upon the end of a pipe. I have therefore provided an adjustable form of thread cutter which may be utilized in dies, particularly of the type illustrated in Figs. 4 and 5, in which the thread cutters are supported upon pivotally connected members. Such an adjustable cutter is illustrated in Figs. 6 and 12 in which the thread cutters 21^x are formed upon steel members 53 which are mounted upon pivots 54 within recesses 55 in the inner walls of the members 26, 27, 28. The ends of the walls are apertured to receive screws 56 having beveled heads 57 which are partially seated in the walls of the members 26, 27, 28 and partially in a suitable recess or grooved portion 58 of the thread cutting member 21^x. It will be obvious that as the screws 56 are forced inwardly the thread cutting members 21^x will be moved about their pivots 54 in such a manner as to provide the necessary taper.

The thread cutter 21^x may be held in its recess by a suitable resilient means such as a spring 55^x seated upon a shoulder in the lower end of the cutter and in a suitable socket in the wall 26.

This spring will serve to hold the thread cutter 21^x in its normal position but will yield as the screw 56 is driven inward to force the cutter into position for taper thread cutting. By forming the recess 55 a little deeper than is necessary to conform to standard depth of thread the thread cutters

21^x may be permitted to expand sufficiently to permit the cutting of threads above as well as below the usual standard cut.

While the preferred form of the invention comprises an externally cylindrical head 70 which may be operated by a wrench having flexible gripping members adapted to clasp and rotate the head either by a continuously rotative or a reciprocating movement it will be understood that the head may be provided with a suitable integral handle or preferably with means whereby it may be detachably secured to a handle or plurality of handles. As illustrated in Fig. 2 the head 16 may be provided with a lug 60 having projections 61 adapted to fit the slots in the end 2 of the handle 1, the head being secured to the handle by the pin 14 the lug 60 desirably being provided with a shouldered portion 62 adapted to be engaged by the shoulder 3 on the end of the handle.

Another very convenient embodiment of the invention is illustrated in Fig. 4 in which the head is composed of a series of 90 sections 26^x, 27^x, 28^x similar to those illustrated in Fig. 5, the end of the section 26^x being provided with extensions 63 adapted to fit the slots in the end 2 of the handle 1, being secured therein by the pin 14. In 95 this case the cutters 21 are carried by the respective members 26^x, 27^x and 28^x as described in reference to Figs. 5 and 6.

Inasmuch as the tool thus constructed is adapted mainly for thread cutting it desirably is provided with two handles extending in axial alinement from the opposite members 26^x, and 27^x. This construction may be made by providing a lug 64 upon the member 27^x, the lug being preferably 105 provided with internal screw threads 65 adapted to engage corresponding screw threads upon a handle 66 which may be of piping of standard size and gage, for example three quarter of an inch piping so 110 that the workman need not carry an additional handle, however, if considerable work is to be done with the tool it is desirable that a regular handle be employed. This handle may, if desired, be equipped with a 115 cylindrical oil can 67 which may be telescopically fitted therein, as illustrated in dotted lines, having a nozzle 68 extending through a suitable aperture in the member 69 and adapted to discharge oil upon the die. By such an arrangement the die may 120 not only be kept well oiled but if desired may be flooded to remove the chips and thus facilitate the action of the cutters.

Thread cutters constructed like those 125 illustrated in Figs. 4 and 6 are particularly advantageous since upon the completion of the thread the sleeve upon the handle 1 may be unscrewed, releasing the locking slide 8 and permitting the sectional cutter 130

to be removed from the work without the necessity of backing the same off. Furthermore the cutter when thus removed and opened as illustrated in Fig. 7 may be conveniently cleaned.

Many other operations may be performed by the mechanisms above described with or without the use of accessory tools. For example the pin 14 may be partially withdrawn from its socket and a wire or rod placed between the pin and head may be bent into any convenient form. The tool is particularly useful in this manner in preparing hangers for pipes and the like since the rod may be either bent around the pin to form an eye or bent around the head to form a loop or may be bent slightly or straightened by the leverage which may be obtained thereon between the pin and the head.

Furthermore suitable cutting devices may be attached to the end of the handle for the purpose of shearing small rods, wires, etc., or a pipe cutter of a usual type having suitable lugs to engage the slots in the end of the handle may be provided and used as an auxiliary tool. The tool may also be used as a jack for the purpose of elevating or spreading objects such for example as elevating a sink or for bending a pipe which is in the way of the workman. In such case the ends of the handles illustrated in Fig. 1 or Fig. 4 may be placed in such a manner as to abut against the object which it is desired to move and against another stationary object and a short pipe thrust into the head, serving as a handle may be used to rotate the compound tool about the axis of the handles. If in such case one of the handles is held from rotation by the operator the unscrewing of the handle from its socket will serve to move the object in the manner desired.

Likewise a piece of pipe having a notched end adapted to engage the cross bars of a bath tub outlet plug seat may be substituted for one of the handle members and the tool rotated in the manner aforesaid to unscrew the plug seat. By this arrangement a powerful tool is provided by which the plug seat may be removed without danger of injuring the enameled tub, which frequently is seriously chipped when improper tools are used for the purpose of removing the plug seat.

The actuator, such as that illustrated in Fig. 1 may also be used conveniently as a vise to hold a pipe or other articles while they are being screw threaded or operated upon in other usual ways. This can be accomplished by unscrewing the handle 13 and screwing the boss 12 or extension of the part 9 upon the hose bib end of the faucet. The pipe to be held from rotation may then be placed within the jaws in the manner

above described and held clamped therein by pressure by the workman upon the handle 7 of the tool. The free end of the pipe may thereupon be threaded in the usual manner by the use of a thread cutter such as that shown in Figs. 3 and 5 rotated by any of the actuators above mentioned.

By thus utilizing the compound tool the workman may readily perform practically all of the operations necessary over the sink so that the chips, oil, etc., may fall into the sink or a paper or receptacle placed therein so that the same may be easily removed.

Various other uses may be made of this compound tool and the parts thereof as will be obvious to any workman skilled in the art of plumbing. It will therefore be understood that the mechanisms shown herein are illustrative of the invention merely and not restrictive and that the invention may be embodied in many other forms or adapted to many other uses within the meaning and scope of the following claims.

Having thus described my invention what I claim as new and desire to secure by Letters Patent is:

1. A compound metal working tool comprising a long, smooth, cylindrical head, internally screw threaded at its ends and having a longitudinal aperture, the wall of said aperture presenting a plurality of inwardly projecting thread cutters and extended guiding ribs adapted to engage the material to be threaded and spaced apart to form holding means for a tool chuck, and means for frictionally engaging the smooth central portion of said head to rotate the same.

2. A compound metal working tool comprising a long smooth cylindrical head externally screw threaded at its ends and having a longitudinal aperture, the walls of said aperture presenting adjacent one end inwardly projecting thread cutters and at the other end extended guiding ribs for the material to be threaded, said ribs being spaced apart to form holding means for a tool chuck, and an actuator comprising a series of pivotally connected members operable frictionally to grasp the cylindrical portion of said head and rotate the same when moved in one direction and to release said head when moved in the opposite direction.

3. A compound metal working tool comprising a head formed of three longitudinal sections hinged together each having a face forming the segment of a cylinder, a screw threading die extending inwardly from each section, means for detachably securing the free ends of said sections together whereby the assembled sections will form a screw cutting die and means for rotating the assembled die.

4. A compound metal working tool com-

prising a head formed of a plurality of longitudinal sections hinged together each having a face forming the segment of a cylinder, a screw threading die extending inwardly from each section, means for detachably securing the free ends of said sections together whereby the assembled sections will form a screw threading die and a removable actuator operable to grasp and 10 rotate said assembled die when moved in one direction and to release the same when moved in the opposite direction.

5. A compound tool comprising a head formed of a plurality of sections hinged together each having an inwardly extending thread cutter, means for detachably connecting the ends of said sections and an actuator comprising a handle and a plurality of flexibly connected members adapted to 20 embrace said head and to rotate the same when moved in one direction and to release the same when moved in the opposite direction.

6. A compound metal working tool comprising a head formed of three longitudinal sections hinged together, a screw cutting die pivotally mounted in each section, means for adjusting said dies radially, means for securing the free ends of the sections together whereby the assembled sections will form a thread cutting die and means for rotating the assembled die.

7. A compound metal working tool comprising a head formed of a plurality of longitudinal sections hinged together each of said sections being provided with a thread cutting member seated in a slot in said section and pivoted at its inner end and a screw having a beveled head engaging said 40 thread cutter at its outer end adapted to adjust the same radially, means for securing the free ends of said sections together to form a thread cutting die and means for rotating the assembled die.

45 8. A compound tool comprising a hollow cylindrical head provided at one end with a plurality of inwardly extending thread cutting members and inwardly projecting ribs forming guides adjacent the other end, said 50 head being screw threaded exteriorly at its ends to engage accessory devices and presenting a smooth cylindrical surface intermediate the screw threaded ends, and an actuator having means adapted to grasp and 55 rotate said head.

9. A compound tool comprising a hollow cylindrical head provided at one end with a

plurality of inwardly extending screw cutting members and externally screw threaded throughout a portion of its length, the remaining portion of the exterior surface of said head presenting a surface adapted to be engaged frictionally by an actuator whereby said head may be rotated directly by an actuator or indirectly through an actuator applied to an accessory device screwed upon the threaded end of said head.

10. A compound tool having at one end a series of inwardly extending thread cutting members and screw threaded externally 70 to afford a means for attaching an accessory device, and means for rotating said head.

11. A compound tool comprising an apertured head consisting of three longitudinal sections hinged together each of said sections being provided with an inwardly extending thread cutting member and externally threaded to afford means for attaching an accessory device and means for rotating said head.

80 12. A compound tool comprising a hollow cylindrical head provided at one end with a plurality of inwardly extending thread cutting members and at its opposite end with inwardly projecting ribs forming 85 guiding bushings, said head being screw threaded externally to receive an accessory device, a tool chuck removably secured in the end portion having the inwardly projecting ribs and an actuator adapted to engage and rotate said head.

13. A thread cutting head for a compound tool consisting of three longitudinal sections hinged together each of said sections being provided at one end with a screw cutting member and at the opposite end with ribs adapted to form guides for the article to be screw threaded and to form holding means for a tool chuck.

100 14. A thread cutting head for a compound tool consisting of three longitudinal sections hinged together each of said sections being provided at one end with a screw cutting member and at the opposite end with ribs adapted to form guides for the article to be screw threaded and to form holding means for a tool chuck, said head being externally screw threaded at its ends to receive accessory members substantially as described.

110 In testimony whereof, I have signed my name to this specification.

MYLES F. MORAN.
